To all whom it may concern:

Be it known that I, HEINRICH RAMPFEL, a citizen of the United States, residing at 591 Central Avenue, Jersey City, in the county of Hudson and State of New Jersey, have invented a new, original, and ornamental Design for Plate or Similar Article, of which the following is a specification, reference being had to the accompanying drawing, forming part thereof.

The figure is a plan view of a plate or similar article showing my new design.

I claim:
